ELLIPOGRAPH

Philip O. Solon, Oakland, Calif.

Application March 1, 1951, Serial No. 213,313

6 Claims. (Cl. 33—30)

1

The present invention relates to improvements in an ellipso graph and its principal object is to provide a mechanical device adapted to greatly facilitate the drawing of an ellipse to any desired specifications within the range of the instrument.

More particularly it is proposed to provide a device of the character described in which a string is used as a guide for the pencil point, the string being arranged in the form of a loop having both of its free ends secured upon a spring-actuated drum so that any desired length of loop may be withdrawn from the drum against spring pressure to correspond to the needed length and breadth for the ellipse to be drawn while the drum automatically takes in any slack or surplus string withdrawn in applying the loop.

It is further proposed to provide means forming a unitary structure with the drum whereby two pins may be positioned, first, to correspond to one of the foci and the opposite end of the major axis of the ellipse to be drawn to secure a proper length of loop, and next, to correspond to both foci to allow the loop to be used for guiding a pencil in drawing the ellipse in one continuous sweep.

It is additionally proposed to provide means whereby, after the loop has been properly positioned with respect to the pins with the aid of the loop tensioning means, an unused portion of the loop may be firmly anchored adjacent the drum to prevent any yielding of the loop in response to the pressure of the pencil as the ellipse is drawn.

It is further proposed to provide a mechanical means for drawing geometrical ellipses of any size or eccentricity within the range of the instrument by making, with the instrument, measurements from focus to focus and from one focus to the opposite end of the major axis, and thereby fixing the exact length of string-loop required for the geometric drawing of the desired ellipse.

Further objects and advantages of my invention will appear as the specification proceeds, and the novel features of my invention will be fully defined in the claims attached hereto.

The preferred form of my invention is illustrated in the accompanying drawing, in which:

Figure 1 shows a perspective view of my ellipso graph,

Figure 2, a side view of a runner used in my ellipso graph, and

Figure 3, a diagram showing the points to be established on the drawing sheet prior to the application of the device.

While I have shown only the preferred form of my invention, I wish to have it understood

2

that various changes and modifications may be made within the scope of the claims attached hereto without departing from the spirit of the invention.

5 Referring to the drawing in detail, my ellipso graph comprises in its principal features a base 1, a bar 2 slidable in the base, a pin 3 projecting downwardly from the end of the bar, and a runner 4 slidable on the bar and carrying a second pin 5, a drum 6, string locking means 7, and a string guide roller 8.

The base 1 may be of any suitable form to give a solid support to the remaining parts, and is here shown as comprising a rectangular block 9 having a flat bottom face 10 and a central substantially square superstructure 11, in which the bar 2 is slidable in a direction transverse to the length of the block. A set screw 12 is adapted for securing the bar in adjusted position.

10 The pin 3 is threaded into the end of the bar vertically and terminates in a point 13 which, in use, is adjusted to a position substantially on a level with the bottom plane of the base 1.

The runner 4 is slidable on the bar 2 between the base and the pin 3 and may be locked in any adjusted position by means of a set screw 14 which is preferably provided with a knurled head. The runner generally comprises a rectangular body portion 15 having a pair of flanges 16 projecting upwardly therefrom and having a second pair of flanges 17 projecting downwardly.

15 The flanges 16 carry the drum 6 which has the free ends of a looped string 18 secured thereto, the ends being wound upon the drum in the same direction. The drum is provided with a clock spring 19 which tends to rotate the drum in a direction for winding the looped string upon the drum but which allows any desired length of loop to be manually withdrawn while the spring keeps the loop under tension.

20 The pin 5 which may also be referred to as a back edge projects downwardly from the runner on the side facing the base substantially to the bottom plane of the base so as to have an easy gliding contact with the drawing sheet in connection with which the device is used. The roller 8 is mounted in the opposite side of the runner, between the flanges 17 and serves to guide the two strands of the loop toward the pin 5 in substantially horizontal direction.

25 Above the roller the runner carries the locking means 7 for the two strands of string, the locking means comprising a pair of spaced rods 20 slidable in the body of the runner in a direction parallel to the bar 2, a short plate 21 carried at

one end of the rods and adapted to bear against the face of the runner for locking the strands of the string thereto and a second short plate 22 mounted upon the other ends of the rods and normally urged away from the body of the runner by a spring 23. Thus the two strands of the string are normally locked to the body of the runner, but may be readily released by pressure brought to bear on the plate 22.

In use, the loop 24 of the string is normally engaged over the pin 3, and intermediate portions of the two strands are guided over the second pin 5 to pass over the guide roller 8 and onto the drum 6. While, for convenience of illustration, the string is shown with wide clearances about the pins, it will be understood that normally the string is under tension and tightly folded upon the pins.

The string 18 is made of non-stretching material, preferably such as is used in a nylon trout-line leader.

In using the device, the draftsman first lays out the essential points of the ellipse to be drawn, as shown in Figure 3. The major axis is marked by the points W and E, the minor axis by the points N and S, the center by the point O and the two foci by the points LF and RF (left and right focus). The location of the foci is obtained by drawing an arc with the radius O—W about the point N; this arc intersecting the major axis at the foci LF and RF.

Next the ellipsograph is applied, with the point of the pin 3 resting on RF, right focus. Pressing on plate 22, so as to release the string, the draftsman adjusts the runner on the bar 2 to bring the pin 5 over the point W, that is the extreme opposite end of the major axis. During this adjustment the drum 6 will feed string or take up string as required, keeping the loop under tension at all times. After the proper adjustment has been made, the draftsman releases pressure on the plate 22, causing the plate 21 to lock adjacent portions of the string upon the body of the runner. That portion of the string looped about the two pins 3 and 5 now exactly corresponds to the length of string required for drawing the ellipse to the desired dimensions.

With the string firmly locked by the plate 21, the draftsman then readjusts the runner to bring the pin 5 over LF (left focus) and locks it by means of set screw 14. This operation slackens the available length of loop. The draftsman then catches the string with his pencil, approximately at the point marked 25, with the pencil disposed on the far side of the device, tensions the string to bring the pencil over the point W, and guided by the string, draws the entire ellipse in one clockwise sweep.

The ellipse thus formed is a true ellipse drawn to the original specifications. It passes through the points W and E, because the total length of string used in each one-half of the operation is equal to the major axis called for, the string being anchored at one focus and doubled opposite the other focus to compensate for that portion of the major axis extending beyond the first focus. It passes through points N and S, because when the pencil crosses the vertical center line, the string forms an equilateral triangle, each side of which is equal to one-half the length of the major axis, and finally, the sum of the distances of any point from the foci remains the same, since the length of the used portion of the string remains the same throughout.

I claim:

1. An ellipsograph comprising a bar, means at the rear end of the bar for horizontally supporting the latter, a pin projecting downwardly from the forward end of the bar, a runner slideable on the bar between the pin and the supporting means, a spool revolvable in the runner above the bar, a second spool revolvable in the runner below the bar in parallel relation to the first spool, a second pin projecting downwardly from the runner rearwardly of the second spool, and a looped string having its ends secured upon the first spool for winding and unwinding operations and having two strands descending from the said spool on opposite sides of the bar and underneath the second spool and around the second pin with the loop of the string engaging over the first pin, the first spool being operable for placing the looped string under tension, and the runner having means for tightening the two strands upon the body thereof.

2. An ellipsograph comprising a bar, means at the rear end of the bar for horizontally supporting the latter, a pin projecting downwardly from the forward end of the bar, a runner slideable on the bar between the pin and the supporting means, a spool revolvable in the runner above the bar, a second spool revolvable in the runner below the bar in parallel relation to the first spool, a second pin projecting downwardly from the runner rearwardly of the second spool, and a looped string having its ends secured upon the first spool for winding and unwinding operations and having two strands descending from the said spool on opposite sides of the bar and underneath the second spool and around the second pin with the loop of the string engaging over the first pin, the first spool having spring means for holding the looped string under tension, and the runner having means for tightening the two strands upon the body thereof.

3. An ellipsograph comprising a bar, means at the rear end of the bar for horizontally supporting the latter, a pin projecting downwardly from the forward end of the bar, a runner slideable on the bar between the pin and the supporting means, a spool revolvable in the runner above the bar, a second spool revolvable in the runner below the bar in parallel relation to the first spool, a second pin projecting downwardly from the runner rearwardly of the second spool, and a looped string having its ends secured upon the first spool for winding and unwinding operations and having two strands descending from the said spool on opposite sides of the bar and underneath the second spool and around the second pin with the loop of the string engaging over the first pin, the first spool being operable for placing the looped string under tension, and the runner having a pair of rods slideable therein underneath the bar and plates supported by the rods forwardly and rearwardly of the runner, one of the plates being operable for locking the two strands upon the runner, and the other plate having spring means urging the former plate into locking position.

4. In an ellipsograph of the character described, a bar, a runner having a body portion adapted for sliding on the bar and having a pair of upwardly projecting flanges above the bar and a second pair of downwardly projecting flanges below the bar, a spool revolvable between the first pair of flanges, a second spool revolvable between the second pair of flanges in parallel relation to the first spool, a looped string hav-

ing its ends secured upon the first spool for winding and unwinding operations and having two strands descending from the said spool on opposite sides of the bar and underneath the second spool, and means for training the strands emerging from the second spool and the looped end of the string to form a pencil guide for drawing an ellipse, the first spool being operable for placing the looped string under tension, and the runner having a pair of rods slideable therein in parallel relation to the bar and plates supported by the rods forwardly and rearwardly of the runner, one of the plates being operable for locking the two strands upon the runner, and the second plate having spring means urging the former plate into locking position.

5. An ellipsograph comprising a bar, means at the rear end of the bar for horizontally supporting the latter, a pin projecting downwardly from the forward end of the bar, a runner slideable on the bar between the pin and the supporting means and having front and rear faces and having a back edge in the lower rear portion thereof, a spool revolvable in the runner above the bar and having a portion projecting forwardly beyond the front face of the runner, guide means on the runner below the bar and forwardly of the back edge and substantially in vertical alinement with the projecting portion of the spool, and a looped string having its ends secured upon the spool for winding and unwinding operations and having two strands descending from the front portion of the spool on opposite sides of the bar and past the guide means in spaced relation to each other, and converging thence toward the back edge and carried around

the same, with the loop of the string engaging over the pin.

6. In an ellipsograph of the character described, a bar, a runner having a body portion adapted for sliding on the bar and having a pair of upwardly projecting flanges above the bar and a second pair of downwardly projecting flanges below the bar, a spool revolvable between the first pair of flanges and having a forwardly presented discharge edge, a guide between the second pair of flanges in parallel relation to the spool and in vertical alinement with the discharge edge of the spool, a looped string having its ends secured upon the spool for winding and unwinding operations and having two strands descending from the discharge edge of the spool on opposite sides of the bar and passing the guide in spaced relation to one another, and means for training the strands emerging from the guide and the looped end of the string to form a pencil guide for drawing an ellipse.
